ALFRED A. MOUSSETTE, OF LEICESTER, MASSACHUSETTS.

ADJUSTABLE SHADE-ROLLER.

1,345,097.

Specification of Letters Patent. Patented June 29, 1920.

Application filed October 9, 1919. Serial No. 329,526.

To all whom it may concern:

Be it known that I, ALFRED A. MOUSSETTE, a citizen of the United States, residing at Cherry Valley, Leicester, in the county of Worcester and State of Massachusetts, have invented a new and useful Adjustable Shade-Roller, of which the following is a specification.

This invention relates to a shade roller of the adjustable type and the principal objects thereof are to provide a construction which can be set up on, and dismounted from a window casing without marring the same at any point that is ordinarily visible from the room; to provide a construction in which the usual solid all wood roll is replaced by one of open construction so that in case of breakage or detachment of the operating spring or other injury, it may be repaired readily by any person, whereas now, said rolls are usually thrown away upon the slightest disarrangement of their parts, because they are all concealed and it is a difficult thing to get at the interior; to provide a construction of this kind in which the usual spring operating and ratchet controlled mechanism can be employed so as to avoid increasing the expense of manufacture by introducing new elements in that part of the device; to provide improvements in the telescoping and supporting mechanism of the roll; to provide an improved supporting bracket and an improved way of connecting it with the rod or roll; to provide an improved way of detachably connecting the shade with the roller, taking advantage of its skeleton character for that purpose; to provide an improved curtain hanger and supporting connection therewith; and to provide improvements in the general construction and arrangement of the parts. Reference is to be had to the accompanying drawings, in which—

Figure 1 is a front elevation of a shade roller constructed in accordance with this invention, showing some parts in section, and illustrating the shade in such a way as to expose the mechanism;

Fig. 2 is an end view of the same taken in the direction of the arrow 2 of Fig. 1;

Fig. 3 is a view looking down on the end of the device in the direction of the arrow 3 of Fig. 2;

Fig. 4 is a transverse sectional view on 55 the line 4—4 of Fig. 1;

Fig. 5 is a side view of a modification, and

Fig. 6 is an end view of the bracket shown in Fig. 5.

The device is shown in the first four 60 figures as mounted on a pair of brackets 10, each consisting of a single separate piece of metal with two opposite flanges 11 projecting therefrom at right angles. Perforations are provided for the holding screws 65 12 which extend into the edge or end of the casing 13 so that they will not mar the front or exposed face of the woodwork.

The object of having two flanges 11 is simply to make the bracket right and left 70 handed so that it can go on either side of the framework, the outer flange 11 may not be needed if this advantage is not desired.

These brackets being secured in position, the two halves 14 and 15 of a central 75 telescoping shaft are fastened to these brackets in fixed position with respect thereto. This is done by passing one end through a central perforation in each bracket and fastening the two shaft sections 80 to the brackets by means of screws 16 or the like. It will be observed that these two shaft sections 14 and 15 telescope with respect to each other so as to provide for any necessary adjustment and that they are 85 fixed by their attachment to the brackets so as to be non-rotatable.

After the telescoping shaft is adjusted to the proper length, it may be, and preferably is, fixed in that position by tightening up a screw 17 carried by a collar 18 which is otherwise loose on the tube 15. This tube has a perforation through it for permitting the screw 17 to engage the surface of the other member 14 of the telescoping shaft. In this way, the two parts are fixed permanently together after they have once been adjusted to proper length.

Mounted on this telescoping shaft are a plurality of rotatable disks 19 three being 100 shown in the present instance. Each of these disks is free to rotate independently but they are connected together by three telescoping rods 20, so as to form a skeleton framework. It will be understood, of 105 course, that I am not limited to the number three, but I find three of these rods to be a most convenient number. Each of them

consists of a small solid rod extending into a tubular or hollow one, so that they are capable of exactly the same adjustment as the central shaft 14—15 so as to accommodate window frames of any ordinary size.

5 The two end disks 19 are limited in motion inwardly by a collar 21 and a ratchet collar 22 which may rotate in contact with the brackets if desired. The ratchet collar 22 is 10 the ordinary ratchet usually employed in shade rollers and gravity ratchet pawls 23 are shown for controlling the motion of the shade roller in the usual way. The usual 15 operating spring 24 is connected in stationary position at one end by the collar 25 on the tubular shaft part 15 and is connected at the other end with the central disk 19. This spring thus operates to draw up the shade in the usual way.

20 On account of this skeleton construction, I am enabled to connect the shade with the roller in a more convenient and practical manner than has been the case heretofore, and also to make the connection detachable. 25 This is accomplished by means of hooks 26 sewed or otherwise attached to the end fold or selvage of the shade and passing over one of the adjustable rods 20 as shown at the top of Fig. 1.

30 The two members 14 and 15 being stationary, I can employ that as a support for a curtain rod and for that purpose, I provide a pair of curtain rod hangers 30, each having a set screw extending through the 35 wall of the same against the shaft 15 or 14 so as to hold the hangers 30 in any desired position. Each hanger is provided with a hook in the form of a wire 33 extending up from it near the end. Each of these passes 40 through a perforation in the end of one of the two members 34 and 35, which telescope together and constitute an adjustable curtain rod.

In addition to the use of the device as 45 above specified, and its mounting on the outside of a window casing, I have provided means whereby it may be mounted if desired on the inside of the casing and this I have shown in the form of a pair of spaced 50 projections 40 on the outer ends of the two members 14 and 15. These projections are adapted to enter two segmental perforations 41 in metal plates 42 screwed to the inside surfaces of the window casing 13. This 55 holds the two parts of the shaft in fixed position, it being understood that they will be secured together by means of screws 17.

This affords a device which is all open 60 and can be put up, taken down, and repaired in a very simple and easy manner, and which will not mar the woodwork or have any detrimental effect thereon of any character, and affords a way of mounting the shade and curtain in a simple manner with 65 a minimum number of parts without inter-

ferring with the ordinary manufacture of the roller spring and ratchet arrangement which can be used with this invention.

Although I have illustrated and described a single form of the invention with only 70 one modification, I am aware of the fact that it can be carried out in other forms without departing from the scope of the invention as expressed in the claims. Therefore I do not wish to be limited to all the details of 75 construction herein shown and described, but what I do claim is:—

1. In a shade roller, the combination of 80 a pair of stationary telescoping members constituting a central support, a skeleton telescoping frame rotatably carried by said support for holding and winding up the shade, and a spring coiled on one of said members and connected with the frame for rotating it on the support. 85

2. In a shade roller, the combination of 90 a pair of adjustable stationary telescoping members, one within the other, constituting a central shaft, a plurality of disks rotatably mounted thereon, and a plurality of telescoping cylinders carried by said disks at equal distances from said shaft for holding and winding up the shade.

3. In a shade roller, the combination of 95 a stationary central shaft consisting of two telescoping parts, a plurality of disks rotatably mounted on said shaft, a plurality of telescoping rods connected with and supported by all of said disks so that the disks and rods together constitute a shade roller, 100 and a spring and ratchet mechanism for operating the roller.

4. In a shade roller, the combination of 105 a stationary central shaft consisting of two telescoping parts, a plurality of disks rotatably mounted on said shaft, a plurality of telescoping rods supported by said disks to rotate therewith, a spring fixedly connected to one of the parts of said telescoping shaft at one end and connected with one of said 110 disks at its other end, and a ratchet mechanism for controlling the operation of the roller.

5. In a shade roller, the combination of 115 a central shaft consisting of two telescoping parts, disks rotatably mounted on said shaft, telescoping rods connected with said disks so that the disks and rods together constitute a shade roller, means for operating the roller, the outer one of said telescoping parts of the shaft having a perforation therethrough, a collar on the outer member, and a set screw in the collar adapted to pass through the perforation to hold the two parts relatively in fixed position. 120

6. In a shade roller, the combination of 125 a central detachable shaft adapted to be mounted in fixed position, three disks rotatably mounted on said shaft, one at each end, and one near the center, three telescoping

ing rods, each consisting of two parts, the opposite ends thereof being fixed to the two end disks and passing through the central disk, a spring connected with the central disk at one end and fixed to the shaft at the other end, and a ratchet mechanism comprising a ratchet collar fixed to the central shaft, and ratchet pawls carried by said disk for coöperation with said ratchet collar.

10 7. In a shade roller, the combination of a central shaft, three disks rotatably mounted on said shaft, one at each end, and one near the center, three telescoping rods, each consisting of two parts, the opposite ends thereof being fixed to the two disks and passing through the central disk, and a ratchet mechanism.

15 8. The combination with a shade roller comprising a stationary central shaft, a plurality of disks rotatably mounted on said shaft, a plurality of telescoping rods connected with and supported by said disks so that the disks and rods together constitute the shade roller, of a shade having a plurality of hooks secured thereto and engaging one of said telescoping rods to detachably connect the shade therewith.

20 9. The combination with an adjustable shade roller having a central shaft, of a pair of brackets therefor, each having a 25 passage therethrough in which one end of

the shaft is fixed, and provided with a flange adapted to extend along the outer edge of a window casing through which the brackets are secured thereto and each having a flange extending over the front surface of the window casing. 35

10. The combination of a pair of stationary telescoping members constituting a central support or shaft, a plurality of disks 40 rotatably mounted thereon, a skeleton telescoping frame carried by said disks for holding and winding up the shade, said central shaft having two spaced projections at each end, and a plate adapted to be mounted 45 on the inner surface of a window casing and having a pair of openings therein for receiving said projections and supporting said shaft in a non-rotatable position.

11. The combination of a central support 50 or shaft, a frame for holding and winding up the shade, said central shaft having two spaced projections at each end, and a plate adapted to be mounted on the inner surface of a window casing and having a pair of 55 openings therein for receiving said projections and supporting said shaft in a non-rotatable position.

In testimony whereof I have hereunto affixed my signature.

ALFRED A. MOUSETTE.
